REINFORCED PLASTIC BUTTON

Forrest G. Purinton, Waterbury, Conn., assignor
to The Patent Button Company, Waterbury,
Conn., a corporation of Connecticut

Application October 24, 1940, Serial No. 362,669

5 Claims. (CL. 24—90)

My invention relates to new and useful improvements in reinforced plastic buttons, and is a companion to those filed by me on October 17, 1940, bearing Serial Numbers 361,647 and 361,648, for Reinforced plastic buttons.

In the companion cases above-mentioned, it was necessary to provide a special form of button back or shell in the manufacture of the button, whereas in the present application, the button is designed and arranged to use a conventional type of button back or shell, thus doing away with the necessity of additional dies for the shell.

An object of the present invention is to provide a plastic button which is reinforced by a button back or shell and wherein the pre-molded plastic body is provided with a plate, on which there is stamped the desired insignia. The plate, in turn, is provided with an upwardly and outwardly and then downwardly extending flange, so that this flange of the insignia plate may be rimmed about the peripheral rim of the button shell, thus lessening the expense in the manufacture of the button.

A further object of the invention is to provide a reinforced plastic button wherein the body or head is pre-molded and has embedded therein an insignia plate which, in turn, forms a peripheral rim for the plastic body and also is provided with a rim to be clenched or clamped about the peripheral shell of the button.

Still another object of the invention is to provide a button that is relatively inexpensive to manufacture, light in weight, pleasing in appearance, and the two parts easily assembled.

With these and other objects in view, the invention consists in certain new and novel arrangements and combination of parts, as will be hereinafter more fully described and pointed out in the claims.

Referring now to the drawing showing a preferred embodiment,

Fig. 1 is a top plan view on an enlarged scale of my new and improved button;

Fig. 2 is a sectional view taken on the line 2—2 of Fig. 1 and showing the button as attached to its garment;

Fig. 3 is a top plan view of the new and improved insignia plate;

Fig. 4 is a sectional view taken on the line 4—4 of Fig. 3;

Fig. 5 is a sectional view showing the pre-molded plastic body with the insignia plate embedded therein; and

Fig. 6 is a sectional view of the conventional button back or shell.

Referring now to the drawing and for the moment to Fig. 6, there is shown the shell 1 with the integral hub 2 and the outwardly and upwardly extending flange 3. The shell has the opening or perforation 4 in the bottom of the hub, as may be seen in the several views. This shell is a conventional type in the manufacture of metal back buttons.

Referring now to Figs. 3 and 4, there is shown what I term the insignia plate 5, which is preferably stamped from relatively thin sheet metal and on the outer surface thereof may be seen the raised insignia 6, which I have shown in the present instance as forming the letters "P B Co," although it will, of course, be understood that any letters or other insignia may be stamped in this plate, depending on the requirements.

20 The plate is provided with the prick-point openings 7 positioned between the letters and the further prick-point openings 8 in the islands of the letters. These openings 7 and 8 form passageways for the flow of the plastic when the plate is molded in the plastic body of the button.

As mentioned in the companion cases, the plate 5 is placed in the mold in an inverted position from that shown, and a plastic pill, preferably of Bakelite, is deposited on the plate. The mold is then closed and heat applied, so that the Bakelite will flow to the desired shape and through the openings 7 and 8, covering the plate to fill up the spaces between the letters and also the islands within the letters.

35 By providing these several openings between the letters and in the islands, all of the plastic material above the plate is well anchored to the main body of the plastic material.

40 From Fig. 1, it will be seen that the outer surfaces of the letters will lie flush with the face of the button and the said letters will form a contrasting appearance with the Bakelite background. These insignia plates may be of different metals, and the letters being of a polished appearance will show up exceptionally well against the black or contrasting background.

It will be seen from Fig. 2 that the plastic material forms the body 9 and the integral hub 10 of the button. When the plastic body is molded, there is formed a cavity 11, which is to receive the shank 12 of the fastener 13. The shank is preferably provided with the flutes 14, as may be seen in Fig. 2. It will also be noticed that the 55 diameter of the shank is greater than the dia-

ter of the bore. However, during an attaching operation, there is great pressure exerted on the button head which is sufficient to drive the prong through the material 15, through the opening 4 in the shell, and well up into the bore 11 in the hub of the button.

It will also be noticed that the shank 12 is pointed, as at 16, to readily pierce the cloth 15 and to cause the prong to wedge itself into the bore above-mentioned during the attaching operation.

Referring again to the plate 5, it will be seen that besides the plate having a central dome-shaped portion, there is provided an upwardly and outwardly extending flange 17, which then extends downwardly to form the additional rim or flange 18.

In the assembling of the button, the pre-molded plastic body, as shown in Fig. 5, with its embedded plate will be tightly fitted within the shell 1.

Thus, the plastic hub will be completely reinforced and likewise the plastic body or head will be reinforced by the shell, as this plastic body follows the general contour of the aforementioned shell 1.

The flange 18 fitting over the upwardly and outwardly extending flange 3 of the shell will be pressed inwardly, as shown in Fig. 2, thus rigidly binding together the shell, the insignia plate, and the plastic body. The surface of the button may then be polished or lacquered. The contrasting insignia within the plastic background framed by the metal flange presents an extremely pleasing appearance.

From the foregoing, it will be seen that I have provided a button consisting of a pre-molded body having a chamber or bore to receive the prong of a fastener. The body is also provided with the insignia plate, which plate not only provides the insignia but reinforces the body and provides a means for clamping the body within the conventional button back or shell.

It will also be seen that the button is one that is relatively inexpensive to manufacture, light in weight, pleasing in appearance, and strong in construction.

Having thus described my invention, what I claim as new and desire to secure by Letters Patent is:

1. A reinforced plastic button including a metal back shell having an upwardly extending peripheral flange, a pre-molded plastic body tightly fitted within the shell, a metal plate having raised insignia stamped thereon embedded in the plastic 55

body and the face of the insignia visible in the plastic body, the said plate being dome-shaped and having a curled peripheral rim, the rim of the shell crimped within the curled rim of said plate to thereby secure the body and shell to each other, and the said plastic body provided with a chamber to receive the prong of a fastener.

2. A tack button including a metal shell having an upwardly extending peripheral flange, a pre-molded plastic body filling said shell, said plastic body having a plate embedded below the top surface thereof and said plate provided with raised insignia visible from the face of the plastic body, said plate being bent back upon itself about its peripheral edge and the rim of the shell crimped within the bent rim of the plate to thereby bind together the plate, plastic body, and shell.

3. A reinforced plastic button including a metal back shell having an upwardly extending peripheral flange, a pre-molded plastic body fitted within the shell, an insignia plate embedded just below the surface of the plastic body and the insignia visible from the surface of the plastic body, said plate extending beyond the plastic body and provided with an upwardly and outwardly and downwardly extending flange to grip the flange of said metal shell, and the plastic body provided with a bore adapted to receive and grip the prong of a fastener.

4. A tack button including a metal shell having a hub, a pre-molded plastic body fitted within the shell and filling said hub, an insignia plate provided with raised portions and said plate also being perforated, the said plate being embedded within the plastic body and having a curled rim extending outwardly beyond the peripheral edge of the plastic body, and said rim secured over the upper peripheral edge of the shell to bind together the plastic body, plate, and shell.

5. A tack button comprising in part a pre-molded plastic body including a hub, the said body and hub fitted within a metal body shell, the said plastic body having a perforated plate embedded therein and slightly below the surface thereof and said plate provided with raised portions visible from the top surface of the plastic body, the said plate also extending beyond the marginal edge of the plastic body to provide a peripheral flange and said flange crimped to the body shell, the said plastic body provided with a bore extending up through the hub to a point short of the embedded plate, and the said bore adapted to act as a receptive chamber for a fastening member.

FORREST G. PURINTON.
